UNITED STATES PATENT OFFICE.

DUDLEY T. FISHER, OF COLUMBUS, OHIO, ASSIGNOR, BY MESNE ASSIGNMENTS, TO THE JEFFREY MANUFACTURING COMPANY, A CORPORATION OF OHIO.

LOCOMOTIVE WITH HAULAGE-CABLE MECHANISM.

1,190,394.

Specification of Letters Patent. Patented July 11, 1916.

Application filed September 20, 1907, Serial No. 393,829. Renewed October 21, 1914. Serial No. 867,905.

To all whom it may concern:

Be it known that I, DUDLEY T. FISHER, a citizen of the United States, residing at Columbus, in the county of Franklin and State of Ohio, have invented certain new and useful Improvements in Locomotives with Haulage-Cable Mechanism, of which the following is a specification, reference being had therein to the accompanying drawing.

In coal mines relatively small cars are used which, while being loaded are separated from each other and scattered over more or less of the mine, one in one room or at one loading point and others at others. The older plan, where animal power was used, was to haul each of these cars singly by an animal from the room, after it had been loaded, to a collecting point where a number of the cars were coupled together to form a train or "trip". Since the introduction of electrical power use has been made for this purpose of "gathering" locomotives, each having a reel with an electric cable thereon, the terminal of which can be connected electrically to a current supplying wire, so that as the car moves away from the source of supply, the cable on the reel will maintain a continuity of electric connection to the motor. In using this apparatus the locomotive is itself run into the rooms successively and coupled to the isolated loaded cars which are thereafter hauled by it to the gathering point. Under many circumstances these gathering locomotives with cable reels cannot be used to advantage, particularly where the mine roof is low or where the track has been hastily constructed, as the branch tracks frequently are which extend from the entry into the room. Under circumstances such as those last referred to, it has been proposed to use in place of the gathering locomotives of the sort above described, locomotives each carrying a haulage cable which can be unwound from a reel and the end taken manually into a mine room and attached to a car, after which it is wound on the reel by suitable driving mechanism to withdraw the car from the room. In earlier locomotives which have been proposed for this class of work it has been only possible to lead the cable off along lines tangential to a vertical reel, the constructions being such that the

cable cannot be led off at any points longitudinally spaced from the reel. It frequently happens, however, that it is desirable to pay the cable out at points remote longitudinally from the reel; that is, in many cases the point at which the cable must be fed out is determined by such factors as, the convenience of the operator in watching the cable, the position of cars with respect to the locomotive, the position of other parts of the locomotive from which the cable must keep clear, etc. But the point of paying out the cable being fixed for reasons such as those above stated it frequently and in fact usually happens that for practical mechanical reasons the reel itself cannot be located at that exact position. For instance in a construction such as I have shown the desire is under most circumstances to feed the cable out at a point near the operator's seat so that the operator can watch the cable closely and prevent fouling; but the space at the operator's end of the locomotive is quite fully occupied by the operator himself and by the devices such as the controller, the brake wheel, etc., which he must have within easy reach. The reel being necessarily large and occupying much space horizontally, especially when a reel with a vertical axis is used, cannot be positioned at the operator's end where it is desired to feed off the cable. And so the reel has been positioned at the opposite end of the locomotive where there is plenty of room for it, and guide devices for the cable have been provided at the operator's end which permit the cable to be led off to the right or to the left under the eye of the operator.

The principal object of the invention therefore is to provide a locomotive of this general class which has means whereby the cable can be led off at a point longitudinally separated from the reel itself. By this construction the relatively small guide devices can be located where the conditions require that the cable be led off and the large heavy reel can be located out of the way of the other locomotive parts where there is plenty of room.

A further object of the invention is to provide a locomotive of this class which has means whereby the cable can be led off at either end. The construction is such that

the guide devices above referred to can be used when the cable is to be paid off at the operator's end. But when circumstances are such as to require the cable to be led off at the other end it is possible to let it extend directly from the reel along tangential lines.

Other objects will be apparent from the following specification and claims.

Locomotives of the class to which my invention relates are to be clearly distinguished from those locomotives of the sort before referred to having electric conductor cables and reeling mechanisms therefor. I am aware that in locomotives having such electric conductor cables it has been proposed to provide means for paying out and taking up the cable at either end. It is to be borne in mind, however, that there are numerous and important differences in construction and in mode of operation between haulage cable locomotives and cable reel locomotives. The haulage cable is usually constructed of steel and has a high tensile strength adapting it to haul cars or even to withstand the entire draft force of the locomotive; the electric cable is usually constructed of copper and has an insignificant tensile strength. The haulage cable is bare and when it is wound in layers upon the reel under high tension, it is able to withstand the compression forces tending to distort it cross-sectionally; the electric cable is provided with a covering of soft insulation which would immediately be crushed and distorted upon being wound upon a reel under high tension. The reel for the haulage cable must ordinarily be below the top plane of the locomotive frame and at such an elevation as to bring the cable approximately at the height of the car couplings; the electric cable reel may be, and, in fact when end-to-end reversibility is contemplated, nearly always is, located either entirely or partly above the top plane of the locomotive frame.

In the accompanying drawings I have shown several forms of mechanism intended to illustrate the scope of the invention. It will be understood that any of the forms shown may be used, or that other forms of mechanism within the scope of the appended claim may be used without departing from the spirit of my invention.

Of the drawings, Figure 1 is a top plan view of a mining locomotive embodying my improvements, some of the parts being indicated conventionally by dotted lines. Fig. 2 is a side elevation of the same. Fig. 3 is an end elevation looking toward the car at the reel carrying end. Fig. 4 is a view showing the reel and the power transmitting devices in vertical central section and showing an electric motor conventionally by outline. Fig. 5 is a rear view of a reel of modified form. Fig. 6 is a vertical

central longitudinal section of said modified form. Fig. 7 is a vertical central longitudinal section of another modified form of reel.

A indicates as a whole a mine locomotive of the type before referred to. Its wheels B are fitted to the track rails. Its body is formed of a heavy cast frame having the side parts C, C, and the end connecting parts D, D. Many of the parts of the locomotive are indicated conventionally by dotted lines. At E the electric motor is situated in the space between the two axles b, b', this motor being geared to one of the axles in any suitable way, and by preference the axles are geared together or connected by chains and sprockets. At F there is a chamber or space left for the motorman and for the locomotive controlling devices which he is called upon to manipulate frequently, such as the wheel of the controller at G and the hand wheel of the brake mechanism at H.

At the end of the locomotive opposite to that where the motorman is placed I arrange a reel for the haulage cable. This is indicated by 1 and is mounted on a vertically arranged shaft or mast 2. This shaft is secured by a base 3 which is in the form of a strong bar extending across from one of the side elements C of the car body to the other, and firmly bolted thereto. The shaft 2 is fastened by a key 4 in this base in such way that it is held firm against rotation. The reel 1 can rotate loosely and freely around this shaft when it is disengaged from the other parts.

8 indicates an electric motor having a suitable field frame and connected to the upper end of the shaft 2 by means of the flange or plate 6 which is rigidly fastened to the shaft by a key at 7 and is firmly bolted to the motor frame.

9 indicates a relatively large spur gear wheel which is mounted upon the shaft 2. Between the reel and the shaft there is a lining or bearing 5, and between the wheel 9 and the shaft there is a lining 10. The linings are of such dimensions and so shaped in relation to each other that the wheel 9 is held normally out of engagement or contact with the reel.

11 is a pinion engaging with the driving wheel 9, this pinion being connected to the vertically arranged shaft 12 mounted in the bearing 15. At the upper end of the shaft there is a bevel wheel 13 which meshes with the bevel pinion 14 on the end of the armature shaft.

The reel can be detachably clutched to its driving mechanism as follows: 17 is a sliding collar mounted on the hub 16 of the reel, this collar having a groove for a shaft band 20 which is held against rotation but permits the collar to revolve within it. 18, 18 are clutch pins (of suitable number) se-

cured to the collar 17 and passing through apertures 19 in the web part of the reel. When the collar is slipped along the reel hub the pins 18 are thrust into engagement with the ratchet at 24 on the hub of the gear wheel 9. The band or ring 20 is moved back and forth by a link and lever system comprising the links 21, each pivoted to the band and pivotally connected to a bell lever 22 which is mounted at 22^a on the base 3.

23 is an operating rod extending to the motorman's place, by which he can move the pins 18 at will and effect the clutching or unclutching of the reel.

15 The cable is indicated at 25. One end is secured to the reel 1, and it may be of any suitable length. It may be taken off directly toward the front of the car, or laterally therefrom. Under most circumstances, however, I prefer to use the mechanism in such way that the cable must extend longitudinally of the locomotive, backward. To permit this, I employ a roller guide, at 26, comprising horizontal rollers 26^a and vertical rollers 26^b. At the other end of the locomotive are roller sheaves 27 and 28 supported by the bracket casting 29, which is secured to the rear cross end part D of the car. From these sheaves 27 and 28, the cable, 30 can be taken in any desired direction.

30 indicates a guard device, preferably formed as a casting and bolted to the base 3. It extends part way around the inner side of the reel, and serves to prevent any cable coils which may be lying loosely around the reel from falling off of the edge.

40 At 31 and 32 there are ribs formed on the casting 3 and at the sides thereof for guiding cable to the reel and also to prevent the falling off of these coils; and to still further insure against the falling of the coils, and the proper guiding of the cable, angles 33 and 34 are fastened to the end cross bars of the car.

45 The master gear wheel 9 is formed with a relatively large cavity or chamber 35 adapted to hold a body of lubricant which gradually passes therefrom to the wearing surfaces of the master wheel 9 and of the reel 1.

50 The manner of using an apparatus of the kind above described will be readily understood. The locomotive is stopped in the mine entry in such position that the motorman can look through the passage-way or the "mouth" into the room. His assistant, the "trip rider," takes the end of the cable and carries it into the room and couples it to the car to be drawn out, the motorman having first by the draw-rod 23 and the sliding collar 17 withdrawn the clutch pins 18 from the gearing thus allowing the cable to freely rotate. After the end of the cable is coupled to the car the motorman can, by means of the rod 23 and the collar 17, thrust

the clutch pins 18 into engagement with the master wheel 9. He then starts the motor 8 and the reel is caused to wind up the cable and draw the car from the room to the track in the entry. When a loaded car is sufficiently close to the locomotive the latter is set in motion by means of its motor E and the loaded car is drawn to the point where the trains or "trips" of several cars are made up.

75 The cable is ordinarily led off from the operator's end over the sheaves 27 and 28 and the operator is in this way enabled to see that the cable runs smoothly over the sheaves without fouling and is enabled to 80 watch the approach of the car and stop the winding of the cable at the proper time.

At the same time the reel is so positioned as not to interfere with the other working parts. As shown it is positioned at the extreme opposite end of the locomotive, but as concerns this it will be understood that there can be variation. The sheaves 27 and 28 being rotatable about vertical axes make it possible for the cable to be led off sharply 90 to the right or to the left as the conditions may require. As before stated it was the practice prior to my invention to lead the cable out directly from a vertical reel thus making the point of feeding entirely dependent upon the position of the reel. By 95 my invention I am enabled to position the reel where most convenient and then to carry the cable longitudinally from the reel to guide devices which permit the feeding out 100 toward one side or the other. And it will be understood that while the use of the guide devices 27 and 28 is ordinarily to be preferred the construction is such that the cable can be led off directly from the reel at 105 the other end of the locomotive when desired.

110 It will be seen that in many respects there can be departure from the details which I have designed in this particular construction without departing from the spirit of the essential features of the invention. Thus, where the car is of such design and its parts are so related as to permit it, the motor and the reel may be inverted in relation to 115 each other. This is illustrated in Figs. 5 and 6 where the motor 8^a is shown as placed underneath, it being secured to bars 3^a, 3^b, which extend laterally out to and are fastened to the side parts C', C' of the car-body. The shaft 2^a is secured to the top of the motor frame and extends upwardly therefrom. The reel 1^a is mounted loosely upon this shaft upon a lining interposed between them. The master gear wheel 9^a is 120 between the motor and the reel, it being driven by the pinion 11^a on shaft 12^a which carries also the bevel wheel 13^a meshing with the motor pin 14^a. In this case the clutch

125 collar 20^a is above the reel and its clutch 130

pins 18^a move downward through the wheel web to engage with the wheel 9^a. The operating rod 23^a and bell lever and links are at the top of the apparatus but are operated in 5 a manner substantially similar to that above described.

In Fig. 7 I have shown still another modification. Here, as in the first modification, the motor is arranged above the reel; in fact 10 the chief difference as compared with the first modification is in the gearing between the motor armature and the reel. A spur-pinion 14^b on the armature shaft meshes 15 with a spur-gear 13^b, which is keyed on an extension of the bevel pinion 11^b. This latter pinion has bearing upon shaft 12^b which is supported by lug 8' depending from the frame of the motor 8^b and by the supporting frame 30^b. Bevel pinion 11^b meshes 20 with the large bevel gear 9^b which is mounted to turn freely upon the shaft 2^b. Beneath the bevel gear 9^b is mounted the reel 1^b, and sliding clutch collar 20^b which is operated by means of the bell-crank 22^b to 25 raise or lower the clutch pins 18^b as in the case of the first modification described.

The available space in a mine locomotive is small as there are narrow limits for the height, for the width and for the length. 30 The reel, when the axis is vertical, must be substantially midway between the sides and there is therefore no room for the motor at the side of the reel. Obviously the motor cannot be in front of the reel as it would 35 then interfere with the cable, and obviously the motor cannot be behind the reel without a corresponding increase in the over-all length of the locomotive and without interfering with the cable when the cable is led backward in accordance with my invention. 40 As a result of the above stated conditions the motor must be located either above or below the reel, preferably above, as in that case the reel can be located in a low-down 45 position without increasing the over-all height of the locomotive. With the motor above or below the reel with the reel axis, when extended, intersecting the central body part of the motor, it is essential to so locate 50 the gearing that it is subjected to the minimum of exposure, that is, toward the center and away from the end of the loco-

motive. By so locating the gearing a number of advantages are attained. One advantage is that the gearing itself is protected 55 from injury which might result from accidental contact with foreign objects; another is that with the gearing removed from the front of the locomotive there is less danger of injury to the trip rider or other mine 60 operatives; and another is that there is less danger of the cable itself becoming fouled in the gearing, because when led forward the cable has no auxiliary guides, whereas when led backward it has auxiliary guides which 65 serve to prevent its displacement.

I do not herein claim as a part of my present invention the specific forms of winding mechanisms which I have shown. In my patent for cable winding mechanism for 70 locomotives No. 1,113,975, based on my divisional application Serial No. 659,629, filed Nov. 10, 1911, I have shown and claimed the specific form of winding mechanism which I have shown in Figs. 1 to 4. 75

What I claim is:

The combination of the locomotive body, having a depressed platform at each end, the track wheels, a motor for driving the track wheels, the reel mounted on one of the 80 depressed platforms, the second electric motor connected to the reel for driving it, the haulage cable secured to the reel, the motorman's support and chamber on the depressed platform at the other end of the frame, the 85 sheave guides for the steel haulage cable at the motorman's end of the platform with their axes in transverse vertical planes in the rear of the motorman's chamber arranged to have the cable deflected from the said sheave 90 guides laterally in either direction at angles to the car equal to, less than, or greater than right angles, said parts being arranged to provide a passage for the haulage cable from one end platform to the other in a 95 horizontal plane below the top of the car driving motor.

In testimony whereof I affix my signature, in presence of two witnesses.

DUDLEY T. FISHER.
